UNITED STATES PATENT OFFICE.

THOMAS C. SHEEHAN, OF JERSEY CITY, NEW JERSEY, ASSIGNEE, BY MESNE ASSIGNMENTS, TO AMERICAN HIGH SPEED PRESS COMPANY, OF NEW YORK, N. Y., A CORPORATION OF NEW YORK.

PRINTING-MACHINE.

1,123,021.

Specification of Letters Patent. Patented Dec. 29, 1914.

Application filed August 29, 1906. Serial No. 332,470.

To all whom it may concern:

Be it known that I, THOMAS C. SHEEHAN, a citizen of the United States, residing at Jersey City, in the county of Hudson and State of New Jersey, have invented a new and useful Printing-Machine, of which the following is a specification.

The present invention relates to printing machines, and particularly to that class of machines known as self-feeding automatic platen presses.

In order to do high class work in one or more colors on this kind of a press, a perfect register of the sheet, as well as a smooth and easy gripper motion, is demanded. My invention provides for these features and also for a novel and improved construction and arrangement of parts in such a manner that the noise and vibration incidental to the operation of the machine are reduced, if not entirely absent.

In carrying out my invention, I provide simple but effective means for placing the sheet in exact position on the registering table, and a gripper mechanism, adapted to travel in a direction parallel to the printing surface of the platen.

Other valuable features, as well as a preferred form of carrying out the invention, are disclosed in the following specification and the accompanying drawings, in which like parts are indicated by like reference numerals, and in which—

Figure 1 is a side elevation of a press embodying my invention. Fig. 2 is a view of the side of the registering devices opposite that shown in Fig. 1. Fig. 3 is a plan of the same. Fig. 4 is a detail view, and Fig. 5 is a detail view of parts of the side registering device.

Referring more particularly to Fig. 1, the reference numeral 1 indicates the side frames of the machine, for suitably supporting the component parts of the same. The said frames are connected in any suitable and convenient manner. 2 indicates the main shaft extending transversely of the machine, and to which motion is imparted by means of the gear 3, meshing with the pinion 4, to which power is applied in any suitable manner. 5 indicates the bed carrying the inking mechanism of well known construction and of which only the outlines are shown. The bed is pivoted in the frame at 6 and oscillates in the well

known manner through the instrumentality of the connection 7 and crank 8 carried by the shaft 2 on one side of the machine. In the present instance, there is shown a pneumatic feeding device 9, of usual construction, and to which power is applied by means of the hose 10 and air cylinder 11, whose piston is operated by means of the rod 12, carried by the eccentric ring 13, on the shaft 14, to which motion is applied by means of the gear 15 meshing with the aforesaid pinion 4. The said gear has a crank to transmit motion to the shaft 16 by means of rod 17 and crank 18. Upon said shaft the delivery gripping mechanism is mounted by means of swinging arms 19, only one of which is seen.

It is not thought necessary to go into details of the construction or operation of the above parts, inasmuch as the same are thought to be well known, and form no part of the invention.

Between the side frames and adjacent to the feed (see Figs. 2 and 3) is located the registering table 20, hereinafter called the table, which is supported on and between brackets 21. The brackets are pivoted on a shaft 22, and are adapted to be swung upward, taking the table with them, so as to permit of an unobstructed view of the interior parts of the machine, and to aid in cleaning or when "making ready". Normally the table and brackets are held in position by their weights, and to this end the brackets are provided with projections 23, which rest upon the side frames. Between the brackets and on the table are mounted the various devices for registering the sheets and placing the same in position for the grippers.

The tapes, 24, pass over the surface of the table, around rolls 25 and 26, and idlers 27. The tapes may be driven in any manner, and carry the sheet from the feed to front registering gages 28. The sheet is carried between the tapes and adjustably mounted friction rollers 29, on a rock shaft 181, and under longitudinal guide bars 30. The latter are adjustably mounted on a transverse slotted bar 31, which further carries an adjustable stop 32.

In order to obtain a perfect side register, I have provided means for gripping the sheet and carrying it sidewise to a predetermined position. This manner of side reg-

istering the sheet works perfectly, and admits of easily changing the side register from right to left, or vice versa.

A side registering block 33 (see Fig. 5), 5 is provided having a plate 34 which is flush with the top of the table. The lower edge of the block over the plate 34 is made slanting to permit the sheets to enter and to hold the edge against the plate and table. The 10 plate 34 has an integral vertically extending portion by which it is secured to the block. This portion also serves as a stop to receive the edge of the paper. The said block is capable of a reciprocating motion, 15 and is so positioned that the sheet in traveling over the tapes passes between the block and the plate, which now move and push or crowd the sheet against the side stop 32. Looking at Fig. 5, this motion would be to 20 the right.

On the block is pivoted a registering gripper 35, which is lifted from contact with the plate 34 while the sheet is being pushed against the side stop. The gripper 25 then acts on the sheet, and carries it back and lets go of it, after which the sheet continues to travel toward the gages.

It will be understood that as the side stop and the register block are adjustably mounted, any size sheet may be registered. Moreover, it does not matter how the sheet is fed on the tapes; when coming opposite the register block, it will be pushed toward the side stop and thence carried back positively to a certain point. In other words, I do not depend upon the pushing of the sheet to register the same, but I depend upon the gripper to always grip the sheet at a certain point and carry it back and side register it at another point. The sheet may be crowded more or less against the side stop, according to the manner in which it is fed to the tapes; but the gripper always acts positively at predetermined points.

45 In order to accomplish the above results, the register block is mounted on a reciprocating or sliding bar 36, to which motion is applied by means of a lever 37, pivoted on a projection 38, and carrying a cam roll 39, 50 co-operating with a cam 40, on the shaft 22, (Fig. 3). A spring 41 keeps the roll in engagement with the cam, and a screw 37^a is provided on the bar 36 for taking up lost motion.

55 For actuating the register gripper 35 I have shown the following means; a friction roll 42 is mounted upon the said gripper arm, and is kept in constant engagement with a bar 43 by means of a spring 44. The 60 said bar is mounted on and rocks with a shaft 45, which, in turn is operated by means of a lever 46, carrying a cam roll 47, which engages a cam 48 on the shaft 22. (See Fig. 1.)

55 The bar 43 extends the entire width of

the table, so that the register block may be placed at any point on the reciprocating or sliding bar 36, without disengaging the roll 42 from the bar 43. Consequently the register gripper will always be in working position.

In practice, I provide two register blocks, one for left and one for right register. When registering to the right, the parts will be in the position shown in Fig. 3. When 75 registering to the left, the block 33 is exchanged with a left-hand one of similar construction, (not shown) but adapted to act in the opposite direction, and the lever 37 is moved to the opposite side of the machine 80 and there pivoted upon a projection 49 and connected to the bar 36. It then co-operates with a cam 50 of similar construction to the cam 40, so it will be seen that when changing register, it is only necessary to 85 change the register blocks and this lever from one side of the machine to the other. Of course the adjustable side stop 32 is moved into position to correspond with the position of the register block, and the screw 90 37^a is moved to the other side of the machine.

On the brackets 21 is mounted a rock shaft 52, carrying a plurality of rubber rollers 53 (see Fig. 4), which serve the purpose of squeezing or crowding the sheet toward the front gages.

The gages are mounted upon a rock shaft 54 which at one side carries a cam roll 55 in engagement with a cam 56. This cam 100 is pivoted on the brackets 21, at 57, and operated by means of a forked connection 58, carrying a cam roll 59, co-acting with a cam 60, on the shaft 22. The shaft 52 is rocked by means of a lever 61, carrying a 105 roll 62, in engagement with a cam 63 on the shaft 22, adjacent to the cam 48.

The operation of the above devices is as follows: The sheet is fed from the feed 9 on the table, when it travels on top of the 110 tapes, till it reaches the front gages 28. Previously the shaft 52 has been rocked, lifting the rollers 53 and allowing the sheet to pass under the same. The side register 33, now acts and crowds the sheet against the 115 side stop 32, and while this takes place the shaft 45 is rocked, this lifting the roll 42 and preventing the register gripper from acting. After the sheet has been pushed against the side stop, the bar 43 on the shaft 120 45, descends allowing the gripper to seize the sheet, and carry it over to perfect the side register. When the shaft 52 is rocked back to bring the rollers 53 down on the paper, the said rollers will descend ahead 125 of the motion of the shaft on account of a spring 64. This will easily be understood from an inspection of Fig. 4. The arms carrying the rollers 53 are pivoted on a block 64^a on the shaft 52 and a pin 64^b 130

holds the arms up. On the pivot 57 is also pivoted a turning lip 65, which is in one piece with the cam 56 above mentioned, and is provided with projections, as 66, upon which the front gages 28 rest. Between these 5 projections the grippers act to seize the sheets. When a sheet has been fed toward the gages 28 and is ready to be acted upon by the grippers, the turning lip turns down 10 and out of the way, inasmuch as it is operated by the means which operates the cam 56. This is done in order to permit the grippers to pass as close to the surface of 15 the platen as possible, and to allow stiff paper to bend into proper position after the grippers have seized it. After the sheet has been seized by the grippers and has traveled to the platen the turning lip and the cam 56 again move upward, thus restoring the front 20 gages to their normal position.

Suitable means for turning the platen upwardly are provided, and in the form illustrated, take the following form: On the platen shaft 162, is a worm gear 163, which 25 meshes with a worm 164, upon whose shaft is a hand wheel 165, (Fig. 1). By turning the hand wheel 165 platen may be moved upwardly and also held firmly in the position shown.

30 Rotary motion is applied to shaft 22 by any means as a train of gears including a gear 166, pinion 167, gear 168 and intermediate gear 169 meshing with the large gear 3. The pinion 167 carries a crank 167^a which 35 connects by means of a rod 170 with the feed table 170^a, for transmitting motion to the same, (Fig. 2). The feed table carries a rack 171 meshing with a gear 172 on a pneumatic roller 173, for oscillating this 40 roller and starting the sheet upon its travel. Suitable guides as 174 are provided for keeping the sheet from coming in contact with parts of the mechanism. Means for feeding the sheet by hand is also provided 45 in the shape of posts 175 to which the feed board may be attached. When thus feeding by hand, the sheet passes over the table beneath friction rollers 176, mounted upon a rockshaft 177. This is actuated by means of 50 a roll 178 and cam 179, whereby the friction rollers are lifted at regular intervals to permit the sheet to pass under them. Gages 180 of suitable construction are mounted on a second rockshaft 181, on which is mounted a lip 182. This is in engagement with another lip 183 mounted on the rockshaft 177. When the lip 182 is pressed down by means 55 of the roll 178 and cam 179, it serves to depress the lip 182 and raise the gages 180 and 129 out of the way of the sheet. These 60 means are of course rendered inoperative when the automatic feed is used.

While I have illustrated and described a preferred form in which my invention may 65 be embodied, and while I have shown it as

it may be constructed when used in connection with a particular type of printing machine, I am aware that many modifications may be made therein, and that the invention can be adapted for use with other types of 70 printing machines by any person skilled in the art without departing from the scope of the invention as expressed in the claims. Therefore, I do not wish to be limited to the particular construction shown and described, but 75

What I do claim and desire to secure by Letters Patent is:—

1. In a printing machine, the combination of a registering table pivotally mounted 80 near one end on the frame of the machine, tapes movable along said table for feeding sheets, adjustably mounted friction rollers for engaging the sheets, a slotted transverse bar, a plurality of longitudinal guide-bars 85 on the transverse bar, and an adjustable side stop on said transverse bar.

2. The combination of a feeding device comprising a series of tapes and means for advancing the tapes, with a laterally movable sheet-registering block, a gripper on said block, a transversely movable bar, means connected with the gripper and movable therewith along the bar for controlling the operation of the gripper in one direction in all positions of the block, means for swinging the gripper in the other direction, a rock-shaft for moving said bar transversely, and means for operating said tape advancing means, said rock shaft, and said 95 block. 100

3. In a printing machine, the combination of a registering table, a transversely adjustable side stop adjacent thereto, means extending across the table for supporting the 105 stop at either side thereof, and means for moving sheets transversely toward the side stop, said means comprising a movable block and a plate movable with the block and flush with the table. 110

4. In a printing machine, the combination of a registering table, means for moving sheets sidewise, said means comprising a movable block and a gripper on the block, a roller traveling with the block for operating the gripper, means for rendering the gripper inoperative when the block is pushing the sheet sidewise in one direction comprising a bar on which the roller runs, said 115 bar being co-extensive with the extent of 120 travel of the roller, and means for moving the bar transversely.

5. In a printing machine, the combination of a registering table, a side stop adjacent thereto, means for moving sheets toward the side stop, said means comprising a movable block and a plate supported by the block and flush with the table, a gripper on the block, and means for rendering the gripper inoperative when the block and 125 130

plate are pushing the sheet toward the side stop.

6. In a printing machine, the combination of a registering table, a side stop adjacent thereto, means for moving sheets toward the side stop, said means comprising a movable block and a plate movable with the block, a gripper on the block, and pivoted means for rendering the gripper inoperative when the block and plate are pushing the sheet toward the side stop, and for causing the gripper to grip the sheet when the block and plate move back.

7. In a printing machine, the combination of a side stop, means for pushing sheets transversely against said stop, and means movable with the first named means for carrying sheets a predetermined distance transversely in the opposite direction from a position against the stop.

8. In a printing machine, the combination of an adjustable side stop, adjustable means for pushing sheets transversely against the stop, and means movable with the first named means for carrying the sheets a predetermined distance away from the stop transversely.

9. In a printing machine, the combination of a side stop, means for pushing sheets against the stop, and means mounted on the first named means for carrying sheets a predetermined distance away from the stop.

10. The combination of a side stop a movable block for pushing sheets against the side stop, a plate thereon for receiving sheets, a gripper pivotally mounted on the block for gripping sheets supported by said plate, a roller on the gripper, and a movable bar for manipulating said roller and operating the gripper.

11. The combination of a side stop a movable block having means for supporting sheets adjacent thereto for pushing sheets against the side stop, a gripper movably mounted on the block, resilient means for

moving said gripper into operative position, a controlling bar for controlling the position of said gripper, and means for moving said bar.

12. The combination of a side stop a movable block for registering sheets against the side stop, a gripper movably mounted thereon, a bar for controlling the motion of said gripper, and a rock shaft on which said bar is mounted.

13. In a printing machine, the combination of a table, means for feeding sheets on said table, front gages, tapes for feeding the sheets to said gages, a side stop, a side register for forcing the sheets against said stop, and means for moving the sheets back from said stop a predetermined distance to side register them.

14. In a printing machine, the combination of a table, a side stop, a side register for forcing the sheets against said stop, means for moving the sheets back from said stop a predetermined distance to side register them, a roller for engaging the sheets, a rock-shaft on which said roller is mounted, and a spring connection between the roller and rock-shaft.

15. The combination of a reciprocable block having a plate secured thereto, and spaced from the bottom thereof, a lever pivotally mounted on said block above the free end of said plate and having an arm adapted to engage the plate at the opposite end, and another arm projecting above the block and having a roller thereon with a bar located in position to receive said roller, and means for moving the bar to operate the lever.

In testimony whereof I have hereunto set my hand, in the presence of two subscribing witnesses.

THOMAS C. SHEEHAN.
